UNITED STATES PATENT OFFICE.

ARTHUR COSSINS, OF NETTLESTEAD, NEAR MAIDSTONE, ENGLAND.

DISPLAY STAND.

Application filed April 3, 1926, Serial No. 99,621, and in Great Britain June 4, 1925.

My invention relates to a stand preferably intended for use upon a counter for the display of goods and more particularly applicable for the display of provisions or perishable goods.

The object of this invention is to provide a simple and effective display stand for provisions or other goods of a perishable nature which will be hygienic in character, attractive in form and which will afford protection for the goods against dust, flies and other insects, and which will at the same time enable the goods to be easily seen by prospective purchasers and having easy means of access so that any of the goods may be readily withdrawn for sale.

According to this invention, I employ a stand preferably comprising a suitable rectangular box form of base constructed of wood or other suitable material and preferably enamelled white. Upon the upper surface of this base is mounted a slab of marble or other suitable material of a hygienic nature, easily kept clean, and which is cool and has a pleasing effect. This slab forms the top of the stand upon which articles for sale, such as meat, fish, butter, cheese or the like may be displayed. Its surface may be readily divided into separate spaces by means of transverse divisions which may comprise suitable wooden strips or the like. Along the front edge of the slab is detachably secured a longitudinal bar having two or more short bars pivoted thereto and adapted to be turned into an upright position to form supports for a cover of gauze or other suitable material intended to enclose the goods and protect them against dust, flies and other insects. Along the back of the slab is provided a small raised shelf and at the rear edge of this is arranged a backboard having one or more hinged doors therein. This backboard serves to support one side of the cover of gauze or other material, whilst the door or doors permit easy access to allow of the extraction of any of the goods displayed without the necessity for disturbing the cover. The cover may conveniently be formed from suitable fine gauze or netting, one edge of which is secured along the upright back and which is shaped to fit over the supports and extends over the top and down the sides and front of the stand. A suitable tape which may be of an elastic nature or whose ends are connected by elastic means is pro-

vided to hold the lower edge of the cover in position. The cover is thus readily detachable and may be easily washed and cleaned.

In order that my invention may be readily understood, reference is made to the accompanying drawings, in which:—

Fig. 1 is a perspective view of a display stand according to my invention.

Fig. 2 is a rear elevation thereof, and

Fig. 3 is a cross section.

Referring to the drawings, the rectangular box shaped base 1 is constructed of wood with corner posts 2 and supports a slab 3 of marble or other suitable material on its upper surface so as to incline slightly toward the front of the stand. The two rear corner posts 2 project at 4 above the slab 3 and form supports for the upright back 5 of the stand in which is arranged a door 6 hinged at 7 along its lower edge so as to open outwardly from the back of the stand to enable the salesman or other attendant to extract articles displayed on the stand through the door 6 when desired which may be provided with a spring catch and a knob to open it. A narrow shelf 8 is arranged behind the slab 3 of marble or the like and in front of the upright back 5.

Along the front edge of the stand is provided a detachable strip 9 adapted to be secured in position by projection pins 10 which are passed through holes in the marble or other slab 3 and engage in suitable sockets 11 provided in the rectangular base 1 as shown in Fig. 3. Three bars 12 are pivotally secured at one end to the back of the strip 9 so that they may be turned down parallel to the bar 9 when not in use or may be turned in an upright position as indicated in Figs. 1 and 3 to serve as supports for a cover to enclose the goods displayed upon the stand. The cover 14 may be made from muslin, gauze, net or other suitable material and is substantially rectangular in form, being open at the back and base but provided with turned down portions to cover the two sides and front of the stand. The cover 14 is secured to the top rail 15 of the upright back 5 by any suitable fastening means such as snap button fastenings or the like. It then fits over the stand and is held on the upright supports 12 at the front, its lower edge being held closely round the edge of the stand by means of a tape 16 or the like provided along the lower edge, the

two ends of the tape 16 being connected at the back by an elastic medium 17 so as to draw it tightly against the stand. This will effectively retain the cover 14 in position 5 and prevent the ingress of flies or other insects. The surface of the slab 3 of marble or the like may be divided into separate spaces by means of transverse partitions 18 adapted to rest upon the surface thereof, 10 and which may comprise wooden or other strips preferably enamelled white. This enables different classes of goods to be separated from each other.

A display stand constructed and arranged 15 according to my invention provides a simple, cheap and effective device for displaying goods on shop counters which will be attractive in appearance and hygienic in character. It will effectively protect the goods against 20 handling by prospective customers and preserve them against flies and other pests, whilst the goods may be easily withdrawn through the door provided at the back when a sale is effected.

25 I claim:—

1. In a display stand, a rectangular box

form base, a marble slab supported on its upper surface, an upright back along one edge, a door in the upright back, a strip along the front edge of the slab, projecting pins thereon which engage in holes in the slab to detachably secure the strip in position, uprights pivotally connected to the strip, a gauze cover, snap button fastenings to secure the cover to the upright back and 35 an elastic strip to hold its lower edge close around the front and sides of the slab.

2. In a display stand, a rectangular box 40 form base, a marble slab supported on its upper surface, an upright back along one edge, a door in the upright back, a strip along the front edge of the slab, projecting pins thereon which engage in holes in the slab to detachably secure the strip in position, uprights pivotally connected to the 45 strip, a gauze cover, snap button fastenings to secure the cover to the upright back, an elastic strip to hold its lower edge close around the front and sides of the slab, and detachable bars to divide the surface of the 50 slab into separate spaces.

ARTHUR COSSINS.
